UNITED STATES PATENT OFFICE.

NICHOLAS M. HABBERSTAD, OF ST. PAUL, MINNESOTA.

SHOE FOR DOUBLETREES.

SPECIFICATION forming part of Letters Patent No. 594,870, dated December 7, 1897.

Application filed April 18, 1895. Serial No. 546,230. (No model.)

To all whom it may concern:

Be it known that I, NICHOLAS M. HABBERSTAD, of St. Paul, Ramsey county, Minnesota, have invented certain Improvements 5 in Evener-Shoes, of which the following is a specification.

My invention relates to improvements in attachments for eveners or doubletrees for wagons, its object being to provide a wear-
iron for the front and bottom of the evener
to prevent the wearing of the bottom of the
evener or the chafing of the evener by the
ends of the singletrees, the iron extending
above the top of the evener, so as to serve as
15 a bearing for the hammer-strap, and being
provided with an opening through which the
draft-pin or hammer passes.

To this end my invention consists in a wear
iron or shoe, preferably of angle-iron shape,
20 so as to give the greatest amount of strength
with the least amount of material, secured to
the front of the evener and provided with a
rearwardly-extending web or plate passing
underneath the evener, through which secur-
ing rivets or bolts may be passed, the iron
25 being also provided with lateral ears adapted
to be riveted to the front of the evener. The
device is formed, as shown, with a central
boss, through which the draft-pin or hammer
30 passes, the boss projecting slightly above the
top of the evener and serving as a bearing
for the hammer-strap. The iron or shoe pref-
erably tapers rearwardly, so as to throw the
35 ends of the singletrees aside when they swing
back, thus preventing their locking.

My invention further consists in the con-
struction and combination hereinafter par-
ticularly described and claimed.

In the accompanying drawings, forming
40 part of this specification, Figure 1 is a plan
view of a portion of a wagon-tongue provided
with an evener and singletrees of the ordinary
construction and having my improved wear-
iron attached thereto. Fig. 2 is a front ele-
45 vation of my device. Fig. 3 is a top view of
the same; and Fig. 4 is an end view of the
same shown applied to the evener, the evener
itself being shown in cross-section.

In the drawings, A represents a doubletree

or evener provided with the singletrees 2, of 50
the ordinary construction, attached to the end
of the evener by means of the clevises 3.

B represents my improved wear-iron, pro-
vided with the rearwardly-extending web or
projection 4, passing underneath the evener 55
and being riveted thereto by means of the
rivet 5, the shoe being further secured in
place by means of the laterally-projecting
ears 6, secured to the evener by the rivets 7.

The device is preferably made of angle- 60
iron inclined rearwardly toward the top, so
that the ends of the whiffle or single trees as
they swing back will be thrown above the
evener to prevent their locking.

In the center of the shoe is formed the boss 65
8, having the hole 9, through which the draft-
pin 10 passes. This boss projects slightly
above the top of the evener, furnishing a bear-
ing for the hammer-strap 11, thus preventing
its wearing the evener. 70

I claim—

1. In combination with an evener, a wear-
iron therefor adapted to be secured upon the
front of the evener, and having a horizontal
plate portion serving as a bed for the evener, 75
the boss having a vertical opening to receive
a draft-pin, and being of slightly-greater
height than the evener, so as to furnish a
bearing for the hammer-strap, and the bevel-
face on each side of said boss to deflect the 80
ends of the connected whiffletrees.

2. The combination with the evener and
whiffletrees, of the wear-iron for said evener
adapted to be secured upon the front thereof,
and having a rearwardly-extended horizontal 85
web serving as a bed for said wear-iron hav-
ing a draft-pin hole in front of said evener so
as to furnish a bearing for the hammer-strap,
the face of said wear-iron being beveled on
each side of the draft-pin hole, so as to deflect 90
the ends of the whiffletrees when brought into
contact therewith.

In testimony whereof I affix my signature
in presence of two witnesses.

NICHOLAS M. HABBERSTAD.
